UNITED STATES PATENT OFFICE

GEORGE B. BOSCO, OF CHICAGO, ILLINOIS

TIMBER CLAMP

Application filed January 9, 1928. Serial No. 245,469.

The main objects of this invention are to provide an improved form of clamp for adjustably securing together two timbers; to provide an improved timber clamp particularly adapted for clamping together the two struts of an adjustable shore; to provide an improved clamp of this kind which is adapted to be supported on one of the struts in position to slidably embrace the other strut; to provide improved gripping means for adjustably securing the clamp to said other strut; and to provide gripping means of this kind which is adapted to increase in its gripping power with an increase in the load sustained by the struts.

An illustrative embodiment of this invention is shown in the accompanying drawings, wherein:

Figure 1 is a side elevation of an improved clamp, showing also portions of the struts to which it is applied.

Fig. 2 is a similar view taken from the opposite side of the shore and showing also the adjusting tool.

Fig. 3 is a vertical section, taken on the line 3—3 of Figure 4.

Figure 4 is a top plan of the shore.

Figure 5 is a detail in side elevation, showing the wedge retracted preparatory to placing the inner strut within the clamp.

A timber clamp to which this invention is applied is adapted for securing together timbers of various kinds, but, in the specific embodiment herein illustrated, the improved clamp is applied to the struts of an adjustable shore.

In the form shown, the shore, to which the improved clamp is applied, comprises a pair of telescoping timbers or struts 1 and 2 adapted to be clamped together by an improved clamp 3 and adapted for initial adjustment by means of an adjusting tool 4.

The strut 1 comprises preferably a post of standard construction, such as a 4 x 4 timber. The post 2 comprises a pair of bars 5 and 6 arranged in substantially parallel spaced relation and connected together at their lower extremities by cross pieces 7. Adjacent the other end of the strut 2, the bars 5 and 6 are secured to the improved clamp 3.

The bars 5 and 6 are preferably 2 x 4 timbers and the bar 5 is slightly longer than the bar 6.

In the form shown, the clamp 3 comprises a fitting, preferably a metal casting, which is supported on the strut 2 and which is provided with a central opening 8 for receiving the post 1, to which the fitting is adapted to be locked by improved gripping means arranged at one side of the opening 8.

The fitting is preferably an integral casting which, in the form shown, comprises a pair of side members 9 and 10, arranged in substantially parallel spaced relation and connected together at one end by an angle bar 11, which forms a shelf for engaging the upper extremity of the bar 6. The side members 9 and 10 are connected together at the opposite end thereof by end pieces 12 and 13 which engage the outer face of the bar 5. The fitting may be rigidly secured to the strut bars 5 and 6 by bolts 14, or other suitable fastening means which extend through the side members 9 and 10.

Formed on the end member 12, is a bearing shoe 15, which overlies the upper extremity of the strut bar 5, and which is adapted for engagement with the adjusting tool 4 for the purpose of obtaining a fine initial adjustment of the struts, as hereinafter described.

Formed in the side members 9 and 10, are slots 16 and 17, respectively, which are substantially triangular in shape and arranged to provide a keyway for a wedge 18. The slot 17 is smaller than the slot 16, so as to accommodate the reduced end of the wedge.

The wedge 18 is fulcrumed in the outer corners of the slots 16 and 17 so as to permit the inner edge of the wedge to swing into and out of engagement with the opposed face of the post 1. Formed on the inner edge of the wedge 18, is a substantially flat bearing surface 19 adapted to abut against the post 1, when the wedge is driven into its operative position. Formed on respectively opposite sides of the bearing surface 19, are tapered ridges 20 and 21 adapted to bite into the post 1. The ridges 20 and 21 are arranged so that, when the wedge is initially driven in-

wardly, both of the ridges bite slightly into the post 1 and then, as the post 1 is driven further, the bearing surface 19 lies substantially flat against the post and only the ridge 21 bites into the post. The ridge 21 is located in the plane of the wedge and the ridge 20 is disposed transversely thereto.

Formed on the wedge 18 adjacent its reduced end, is a shoulder 22 adapted to rest on the lower edge of the slot 17 when the wedge is partly withdrawn from its keyway, as shown in Figure 5, so as to facilitate the insertion of the post 1 into the opening 8.

Formed on the wedge 18 adjacent its reduced end, is a shoulder 23 adapted to engage the side member 10 to secure the wedge against withdrawal when the wedge occupies the retracted position shown in Figure 5. Formed on the wedge adjacent the shoulder 23, is a lug 24, located in the plane of the wedge and adapted to engage the side member 10 for securing the wedge against withdrawal when it occupies its operative position. The slot 17 is sufficiently wide, adjacent its upper edge, to clear the lug 24, as shown in Fig. 5, so as to enable the wedge to be shifted to its retracted position.

The tool 4, by which the shore may be initially adjusted, comprises a supporting member in the form of a substantially U shaped stirrup having a pair of side members 25 connected together by an end member 26. The stirrup embraces the post 1 and is provided with a removable locking pin 27 securing it against withdrawal. Pivotally mounted on the side members 25, is an operating lever 28 having a cam 29 adapted to engage the bearing shoe 15 for lifting the strut 1.

40 In operation, a rough adjustment of the shore is obtained by manually lifting the strut 1 to approximately the required height. The tool 4 is then moved downwardly on the post 1 until the cam 29 rests on the bearing shoe 15. By lowering the lever arm 28, the strut 1 may be lifted further to obtain the fine adjustment. After the shore has been adjusted, the wedge 18 is driven into its keyway, causing both of the ridges 20 and 21 to

45 initially bite into the post 1 and then causing the bearing surface 19 to lie flat against the post, thereby retracting the ridge 20 and leaving only the ridge 21 embedded.

Although but one specific embodiment of 55 this invention has been herein shown and described, it will be understood that certain details of the construction shown may be altered or omitted without departing from the spirit of this invention as defined by the 60 following claims.

I claim:—

1. A clamp of the class described comprising a fitting having an opening extending therethrough for receiving a timber and having a keyway located on one side of said open-

ing, a wedge fulcrumed in said keyway, the inner edge of said wedge having a flat bearing surface adapted to abut against the adjacent face of the timber, and tapered ridges formed on said inner edge on respectively opposite sides of said bearing surface and adapted to bite into the timber, one of said ridges being disposed transversely of said bearing surface, the other of said ridges being disposed transversely of the plane of said wedge. 70

2. A clamp of the class described comprising a fitting having an opening extending therethrough for receiving a timber and having a keyway located on one side of said opening, a wedge fulcrumed in said keyway so as 80 to be swingable into different planes, said wedge being tiltable toward said opening for gripping the timber and being tiltable in the opposite direction to a retracted position for releasing the timber, and a shoulder on said 85 wedge adapted to engage a part of said fitting for holding said wedge in said retracted position.

3. A clamp of the class described comprising a fitting having an opening extending 90 therethrough for receiving a timber and having a keyway located on one side of said opening, a wedge fulcrumed in said keyway, said wedge being tiltable toward said opening for gripping the timber and being tiltable in the 95 opposite direction to a retracted position for releasing the timber, and a shoulder on said wedge adapted to engage a part of said fitting for holding said wedge in said retracted position when said wedge is partly withdrawn 100 from said keyway, said shoulder being disengaged from said fitting part by the longitudinal movement of said wedge into said keyway.

4. A clamp of the class described comprising a fitting having an opening extending therethrough for receiving a timber and having a keyway located on one side of said opening, a wedge fulcrumed in said keyway, said wedge being tiltable into one position for 110 gripping the timber and being tiltable into a retracted position for releasing the timber, a lug located on one end of said wedge and adapted to engage a part of said fitting for 115 securing said wedge against withdrawal from said keyway when said wedge occupies said one position, and a shoulder located adjacent said lug for engagement with said fitting to secure said wedge against withdrawal from 120 said keyway when said wedge occupies its retracted position.

5. A device of the class described comprising a pair of side members arranged in substantially parallel spaced relation and adapted to embrace a timber, a pair of end members connecting said side members together, said end members having parts projecting inwardly toward each other to form shelves for engaging the extremity of a strut, and gripping 130

means on said side members for engagement with the timber.

6. A device of the class described comprising a pair of posts of different lengths arranged in substantially parallel spaced relation, a strut slidably arranged between said posts, a fitting comprising an integral casting embracing said posts and strut, said fitting having a keyway at one side thereof, a wedge arranged in said keyway and adapted to grip said strut, a shelf located adjacent said keyway and engaging an extremity of the shorter of said posts, a shelf formed on the opposite side of said fitting and engaging an extremity of the longer of said posts, and means for securing said fitting to said posts.

Signed at Chicago this 6th day of January, 1928.
